VAPOR GENERATOR AND SUPERHEATER

Charles H. Woolley, Cranford, N. J., assignor to
The Babcock & Wilcox Company, Rockleigh,
N. J., a corporation of New Jersey

Application June 23, 1949, Serial No. 100,854

3 Claims. (Cl. 122—336)

1

The present invention relates to a vapor generating installation which will be exemplified herein as a water tube steam generator of the radiant type. The main object of the invention is the provision of a vapor generator of the radiant type which is particularly characterized by its high steam generating capacity relative to the floor space occupied by the installation.

A further object of the invention is the provision of a vapor generator of the character described which is particularly adapted and specially designed for the burning of pulverized solid fuels at relatively high rates of heat release without danger of fouling the surfaces of the convection section of the installation by slag constituting the incombustible residue of such fuels.

Another object of the invention is a vapor generator characterized by low construction costs and low maintenance.

More specifically the invention involves the provision of a vapor generator including a large volume fluid cooled furnace fired by pulverized fuel burning means, the position of fuel introduction and the position of the exit of the products of combustion from the furnace being such that ash particles released by combustion are cooled in their downward flow and are deposited in a subjacent space.

The various features of novelty which characterize the invention are pointed out with particularity in the claims annexed to and forming a part of this specification. For a better understanding of the invention, its operating advantages, and the specific objects attained by its use, reference should be had to the accompanying drawings and descriptive matter in which there is illustrated and described a preferred embodiment of the invention.

In the drawings:

Fig. 1 is a vertical section; and

Figs. 2 and 3 are detail horizontal sections on the lines 2—2 and 3—3 of Fig. 1.

The drawing discloses a vapor generating installation having a vertically elongated furnace or combustion chamber 10 the boundary surfaces of which are mainly defined by vapor generating tubes communicating with the vapor and liquid drum 12. One such boundary surface is shown at 14 as defined by the wall tubes 16 extending from the lower header 18 to the upper header 20 which, in turn, is connected by the roof defining tubes 21 to the drum 12. The rear wall 24 is defined at least in part by downcomer tubes 26 extending from the submerged lower drum 28 and connected to the lower header 30. The re-

2

mainning upright walls of the combustion chamber are similarly defined by upright vapor generating tubes such as those indicated at 32 having their lower ends connected to the lower header 34. The upper ends of all of the steam generating tubes are in communication with the steam space of the drum 12 through appropriate headers and tubes, and the lower ends of the tubes are, for the purposes of natural circulation, in communication through headers such as 18, 30, and 34, and their appropriate connections with the lower drum 28.

In addition to the downcomers 26 which are connected to the header 30, the latter has connected thereto the lower ends of steam generating tubes 36. The lower parts of these tubes extend along the wall 24 and their intermediate parts form the tubular screens 38 and 40 extending across the gas inlet 42 of the gas pass 44 of the convection section. The upper parts of these steam generating tubes define the division wall 46 and beyond this wall these tubes continue to a point of connection with the drum.

At a position above the tubular screens 38 and 40, there is an auxiliary heater exemplified by a high temperature superheater section consisting of a bank of tubes 48. This bank of tubes is formed by a plurality of return bend sections connected in series and having corresponding inlet 25 and outlet ends connected to the inlet header 50, and their opposite ends connected to the outlet header 52.

Above the high temperature superheater section 48 is a low temperature superheater section 56 including superposed banks of tubes 57 and 58 formed by series connected return bend sections. The inlets of these sections are connected by tubes such as 60 and 62 to the steam space of the drum 12.

Steam flows from the outlet header 66 of the lower temperature superheater section 56 through an external tubular connection 70 to a tubular junction member 72 which may have therein a valve such as 74 pivoted at 76 and controlled from steam flow from the header 52 and from the temperature of the steam leaving the header 66, to divide and variably proportion the flow of steam between the tubular connection 80 and a bypass connection 82.

The tubular connection 80 leads to an attenuator which may include a bundle of tubes such as shown at 84, submerged in the drum 28. The part of the steam which flows through this bundle of tubes is lowered in temperature, then passes through the tubular outlet connection 86 to a point of junction 88 with the bypass connection

82. From this point the mixed steam flows to the header 50 and thence through the tubular sections of the high temperature superheater section 48 to the outlet header 52 and thence to a point of use. The attemperated steam is mixed with the bypassed steam in passing to the header 50 and the final temperature of the steam is thus controlled and maintained within permissible limits.

The furnace gases flowing upwardly from the superheater sections turn at the upper end of the gas pass 44 and pass across the elements of two banks of tubes such as those indicated at 90 and 92. These tubes directly connect the drums 12 and 28.

After passing across the bank of tubes 92 the gases flow upwardly through the duct or flue 94 to a regenerative air heater 96, and the combustion air heated thereby flows from the air heater 96 through ductwork 98 to an enclosure 100 from which secondary air is supplied to the burners such as 102 and 104. These burners, as indicated by the drawing, effect downward firing of the furnace 10, and when pulverized coal is used as fuel, the temperature of the furnace gases and particles of ash suspended therein is sufficiently lowered by the furnace wall tubes to prevent fouling of the surfaces of the convection superheaters within the gas pass 44.

To attain high superheated steam temperatures and yet provide a unit which may be started up with a minimum hazard to the superheater located close to the furnace gas outlet, the superheater elements are arranged horizontally so that they may be drained or blown-out before or during the starting up period.

The zone of high temperature in the furnace is at the top but the furnace is elongated in its vertical dimension, and the down-firing burners are so distributed that when all burners are in operation the products of combustion pass downward and are cooled to an adequate ash temperature by the time they are directed in a 180° turn above the front to back hopper and enter the vertical superheater pass.

The illustrative installation provides a combined unit which is inherently simple in construction, rugged and durable in operation, and readily cleanable.

The construction is free of baffles in confined locations and no short gas turns are involved, so that uniform heat transfer conditions result with respect to high temperature heat absorbing surfaces, making for better utilization of the surfaces in attaining maximum heat absorption rates.

The furnace and convection pass construction is simple, the side walls involving the upper and lower headers, such as 34' and 34, extending at the same elevation from the front wall to the rear wall, with provision of an intermediate junction header 35' at a position near the upper part of the high temperature superheater section, so that more widely spaced side wall tubes 36' are used in the upper portion of the superheater pass and the gas turning space 89 forwardly of the saturated boiler bank.

The gas collecting chamber 93 rearwardly of the saturated bank is shown as connected for gas delivery to the air heater located above the unit. When the plant design is such that the stack is supported at ground level, or when it is advantageous to arrange the fan at such a low level, then the gas outlet to the air heater may be arranged rearwardly, or downwardly from the chamber 93.

In the particular form of the invention shown by the drawing, it is to be noted that the inlet tube sections 60 and 62 of the low temperature superheater section pass downwardly on the forward side of the gas turning space 89, then angle across the upflowing gas stream to a position below the submerged drum 28. These sections thus present heat absorbing surfaces and are arranged to provide for expansion between the position where they pass through the upper roof section 91 and where they connect to the superheater section 56. They are preferably supported on the walls of the superheater pass.

The illustrative installation has an operating pressure of 875 p. s. i. and a peak capacity of 450,000 pounds per hour. Its total steam temperature is 915° F. at a 25,000-450,000 steam capacity range. Its feed water temperature is 385° F. at 450,000 pounds per hour.

20 In the illustrative installation, wall tubes of the furnace 10 are closely spaced or contiguous tubes, as indicated in Fig. 2 of the drawings, with the sides of the tubes fully exposed to the furnace.

The installation also includes the two-drum and 25 saturated tube bank arrangement involving components 12, 28, 90, and 92, with downcomers 26 leading to the lower furnace wall headers such as 18, 30, and 34, shielded by the risers, or steam generating tubes 36. With this arrangement, the 30 supply of vaporizable liquid to the furnace walls is from the lower drum 28. The circulating characteristics of the unit, and particularly the two-drum saturated bank of tube arrangement, are such that the liquid supply for the furnace walls 35 may usually be taken from the lower drum.

The supply of liquid to the tubes defining the furnace walls is from the upper steam and water drum 12 through the saturated bank of tubes 92, the lower drum 28 and the shielded downcomer tubes 26, while the adjacent ends of the tubular elements of the banks of superheater tubes 56 are supported by the downcomer tubes 26, the latter being pendentively supported from the lower drum 28.

45 All the tubes and headers, comprising the saturated steam structure, are supported from a common top level represented by the beam 103 so that all of the elements of that structure expand downwardly together. Pendent supports connect 50 the upper steelwork, represented by the beam 103, with the saturated elements. Examples of such pendent supports are indicated at 105, 107, and 109.

The lower front wall header 18 and the side 55 wall headers 34 are supplied with vaporizable liquid by direct extensions, such as 110-114, of some of the downcomer tubes 26 or by junction connectors from the header 30.

While in accordance with the provisions of the 60 statutes there has been illustrated and described a preferred form of the invention, those skilled in the art will understand that changes may be made in the form of the apparatus disclosed without departing from the spirit of the invention as 65 indicated by the subjacent claims, and that certain features of the invention may sometimes be used to advantage without a corresponding use of other features.

What is claimed is:

1. In a vapor generating unit, a furnace the walls of which are defined by upright vapor generating tubes, burner means for firing said furnace at its upper part, some of said tubes defining an upright wall common to the furnace and 70 an upright gas pass disposed alongside the upper

portion of the furnace and having a gas inlet communicating with the lower part of the furnace, parts of the last mentioned wall tubes being disposed as horizontally inclined screen tubes extending across the gas pass gas inlet to the rear wall of the furnace, an elevated vapor and liquid drum adjacent the top of the gas pass, a liquid drum at a level beneath that of the vapor and liquid drum, but intermediate the height of the gas pass, a bank of upright fluid heating tubes directly connecting said drums and disposed transversely of gas flow from the upper part of the gas pass, means connecting the vapor discharge ends of said vapor generating wall tubes with the vapor and liquid drum, downcomer means for connecting the inlet ends of the vapor generating wall tubes with said liquid drum, a superheater including a bank of vertically spaced horizontally disposed tubes extending transversely of the flow of gas in the lower part of said gas pass and in proximity to said screen, means connecting the vapor space of the vapor and liquid drum to the inlet of the superheater, and hanger means pendently supporting said drums and said bank of tubes, said downcomer means including downcomer wall tubes extending downwardly from said liquid drum along the rear wall of the gas pass and the subjacent rear wall of the furnace, said downcomer tubes being also pendently supported by the liquid drum and being thermally protected at their lower portions by a row of lower parts of the common wall vapor generating tubes disposed between the downcomers and the interior of the furnace.

2. In a vapor generating unit, a furnace the walls of which are defined by upright vapor generating tubes, burner means for firing said furnace at its upper part, some of said tubes defining an upright wall common to the furnace and an upright gas pass disposed alongside the upper portion of the furnace and having a gas inlet communicating with the lower part of the furnace, parts of the last mentioned wall tubes being disposed as horizontally inclined screen tubes extending across the gas pass gas inlet to the rear wall of the furnace, an elevated vapor and liquid drum adjacent the top of the gas pass, a liquid drum at a level beneath that of the vapor and liquid drum, but intermediate the height of the gas pass, a bank of upright fluid heating tubes directly connecting said drums and disposed transversely of gas flow from the upper part of the gas pass, means connecting the vapor discharge ends of said vapor generating wall tubes with the vapor and liquid drum, downcomer means for connecting the inlet ends of the vapor generating wall tubes with said liquid drum, a superheater including a bank of vertically spaced horizontally disposed tubes extending transversely of the flow of gas in the lower part of said gas pass and in proximity to said screen, steam supply tubes connecting the vapor space of the vapor and liquid drum to the inlet of the superheater and having parts disposed within the gas pass between the superheater and said bank of tubes, and hanger means pendently

supporting said drums and said bank of tubes, said downcomer means including downcomer wall tubes extending downwardly from said liquid drum along the rear wall of the gas pass and the subjacent rear wall of the furnace, said downcomer tubes being also pendently supported by the liquid drum and being in communication with the interior of that drum.

3. In a vapor generating unit, a furnace the walls of which are defined by upright vapor generating tubes, burner means for firing said furnace at its upper part, some of said tubes defining an upright division wall common to the furnace and an upright gas pass disposed alongside and rearwardly of the upper portion of the furnace and having a gas inlet at its lower end communicating with the lower part of the furnace, parts of the division wall tubes being disposed as horizontally inclined screen tubes extending rearwardly from said division wall across the gas pass gas inlet to the rear wall of the furnace, an elevated vapor and liquid drum adjacent the top of the gas pass, a liquid drum at a level beneath that of the vapor and liquid drum but above the screen tubes and said rear wall of the furnace and intermediate the height of the gas pass, a natural circulation bank of upright fluid heating tubes directly connecting said drums and disposed transversely of gas flow from the upper part of the gas pass, means connecting the vapor discharge ends of said vapor generating wall tubes with the vapor and liquid drum, downcomer means for connecting the inlet ends of the vapor generating wall tubes with said liquid drum, a superheater including a bank of vertically spaced horizontally disposed tubes extending transversely of the flow of gas in the lower part of said gas pass and in proximity to said screen at a position substantially below the level of said liquid drum, the superheater also including header means disposed exteriorly along the rear wall, means connecting the vapor space of the vapor and liquid drum to the inlet of the superheater, and hanger means pendently supporting said drums and said bank of tubes, said downcomer means including downcomer wall tubes extending downwardly from said liquid drum and pendently supported thereby.
